FOREIGN PATENT DOCUMENTSBR DI71007989 F 5/2014
JP 1155970 S 10/2002*Primary Examiner* — Ian Simmons*Assistant Examiner* — Keith Frank(74) *Attorney, Agent, or Firm* — The Webb Law Firm(57) **CLAIM**

The ornamental design for a container for beverages or food, as shown and described.

DESCRIPTION

FIG. 1 is an upper left front perspective view of a container for beverages or food showing my new design;

FIG. 2 is a front view thereof;

FIG. 3 is a right side view thereof;

FIG. 4 is a rear view thereof;

FIG. 5 is a top view thereof; and,

FIG. 6 is a bottom view thereof.

The broken lines in the drawings showing the container for beverages or food illustrate the portions that form no part of the claimed design.
